(57) **CLAIM**

The ornamental design for a quick-fitting pipe coupler as shown and described.

DESCRIPTION

FIG. 1 is a top, right, front perspective view of a quick-fitting pipe coupler showing our new design;

FIG. 2 is a bottom, left, rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a front elevation view of the quick-fitting pipe coupler of FIG. 1, shown in an alternate configuration in a condition of use for clarity of disclosure.

The broken lines illustrate portions of the quick-fitting pipe coupler and form no part of the claimed design.
